UNITED STATES PATENT OFFICE.

GEORGE T. JOHNSON, OF COLUMBUS, OHIO, ASSIGNOR TO THE BUCKEYE STEEL CASTINGS COMPANY, OF COLUMBUS, OHIO.

SPRING PLANK.

Application filed January 4, 1927. Serial No. 158,948.

This invention relates to car trucks characterized by having a large number of springs arranged under the bolster and has special reference to the spring plank mounting, the object being to provide a novel form of spring plank by which the removal of the side frame may be accomplished without materially disturbing the bolster, springs, and spring plank. The invention is illustrated 5 in the accompanying drawings and will be hereinafter fully described, the novel features being particularly pointed out in the appended claims.

In the drawings, Figure 1 is a side elevation of a car truck having the present invention embodied therein;

Figure 2 is a section, on a larger scale, taken through the bolster and the side frame substantially in the medial vertical longitudinal plane of the side frame;

Figure 3 is a horizontal section on the line 3—3 of Fig. 2;

Figure 4 is a horizontal section and plan illustrating another embodiment of the invention, and

Figure 5 is a section on the line 5—5 of Fig. 4.

The side frame of a car truck embodying the present invention comprises a top member 1, a bottom member 2, and columns 3 connecting the top and bottom members and defining an opening to receive the ends of the bolster 4 and spring plank 5, the journal boxes 6 being preferably integral with the side frame. Spring seats 7 are formed on the lower member of the side frame adjacent the bases of the columns and the spring plank is adapted to occupy the space between these seats, the springs 8 and 9 being carried by said seats and by the spring plank, and it will be noted that this construction will accommodate a large number of springs, the end springs being supported by the seats on a higher level than the central group. The spring plank is preferably of pressed steel, although it may be cast, and is in the form of a shallow trough, as shown most clearly in Fig. 1, and rests upon the lower member of the side frame between the 45 spring seats 7 and is held against relative

endwise movement by the well-known interengaging sockets and lugs as indicated at 5^a Figs. 1 and 2. The bolster is recessed at its ends on its bottom, as at 9^a, to accommodate the higher end springs, the setting of 55 the end springs on a higher level affording an advantageous distribution of metal in the bottom of the lower member of the side frame.

In the constructions shown in Figs. 1 to 3 inclusive, the inner sides of the spring seats 7 are straight and the upstanding side flanges of the spring plank are straight and the seats 7 each support only a part of the spring resting thereon. To provide support 60 for the remaining portion of the spring there is a shelf 10 projecting inwardly from the upper edge of each flange of the spring plank which shelf is reenforced by a rib 11. If the spring plank be cast, the shelf and 65 ribs will, of course, be integral with the flange, but if the plank be pressed, a separate forging or bracket may be riveted on. The edge of the shelf is preferably convex 70 to fit between the outer springs of the central group of springs, and the slight space between the spring plank and the seat 7 is or may be bridged by a wear plate or shim 12 resting on the seat and having the shelf and downturned lips or flanges 13 to engage 75 the inner and outer sides of the seats, these lips or flanges being of less depth than the height of the interengaging lugs between frame and spring plank. The end springs rest on the wear plate or shim 12, and a wear 80 plate or shim 13^a on the spring plank receives the central group of springs. In Figures 1, 2 and 3, the height of the spring plank flange is the same as the height of the spring seat 7 so that the upper surfaces 85 of the shelf and the seat are flush. In Figures 4 and 5, the seat 7 is of less height than the flange of the spring plank 14 and an outwardly extending shelf 15, as well as the inwardly extending shelf 16, is provided, the 90 shelf 16 being the same as the shelf 10 in all respects while the shelf 15 projects over and rests upon the spring seat. A shim or wear plate 18 may be used, if desired.

The various shims or wear plates may be 100

of any desired thickness and if the ribs 11 should be reduced in width, so that the shelyes overhang, it will not be necessary to employ shims of special design and they 5 may be provided in such number and of such thickness as to maintain the coupler at the required height from the track rails.

When used with a side frame and bolster provided with suitable engagement features, 10 the construction shown in Figures 1 to 5, if the spring plank be jacked up so as to clear the lugs by which it is retained on the side frame, the spring plank, springs, and bolster will be stable if supported in the 15 raised position, and the side frame may be easily removed leaving the bolster, springs and spring plank intact, as well as other parts for which the bolster or spring plank form supports.

20 Having fully described my invention what I claim as new and desire to secure by Letters Patent, is:—

1. A spring plank having upstanding side flanges at its outer end portions and adapted 25 to carry a group of springs between its flanges, and shelves projecting inwardly and outwardly from its flanges to support additional springs at a higher level than the first-mentioned springs.

30 2. The combination of a side frame, spring seats on the lower member of the side frame, a spring plank resting on the side frame between the spring seats and having inwardly projecting shelves, springs supported on the 35 spring seats and partially on said shelves, and a group of springs carried by the spring plank at a level lower than the spring seats.

3. The combination of a side frame, spring seats on the lower member of the side frame 40 having their side edges straight and transverse to the side frame, a spring plank resting on the side frame between the spring seats and having straight sides fitting close to the straight sides of the spring seats, 45 shelves inwardly of the sides of the spring plank coacting with said spring seats, springs carried jointly by the spring seats and the shelves, and springs carried by the spring plank at a lower level than the first-mentioned springs.

50 4. The combination of a side frame provided with spring seats, a spring plank carrying spring seats, a plurality of springs for supporting a bolster, certain of said springs resting partially upon the spring seats on the side frame and partially upon the spring seats on the spring plank.

5. The combination of a side frame provided with spring seats, a spring plank 60 carrying elevated spring seats, said spring plank having removable interlocking engagement with the side frame, a bolster, a group of springs interposed between the spring plank and the bolster, and other 65 springs under the bolster and resting at their

lower ends partially over the spring seats on the side frame and partially on the said elevated spring seats on the spring plank, the said spring seats on the spring plank being such that when the spring plank is 70 raised from its interlocking engagement with the side frame, the latter may be moved laterally without otherwise disturbing the spring plank or superimposed parts.

6. The combination of a side frame provided with spring seats, a spring plank having upstanding side flanges and adapted to provide spring seats between said upstanding flanges, and spring seats inwardly of said flanges and positioned to assist in supporting springs seated on the spring seats of the side frame. 75

7. The combination of a side frame and a spring plank having upstanding flanges at its outer end portions and adapted to carry 85 a group of springs between its flanges, shelves extending from the flanges of the spring plank and positioned to assist in supporting additional springs, and other seats to receive lower end portions of said additional springs. 90

8. The combination of a side frame and a spring plank, the latter having upstanding side flanges at its outer end portions and adapted to carry a group of springs between 95 its flanges, and shelves inwardly of said flanges to assist in supporting additional springs at a higher level than the first-mentioned springs, and supporting means for such additional springs laterally of the upstanding flanges of the spring plank. 100

9. The combination with a side frame, of a spring bearing member having interlocking engagement with the side frame and adapted to carry some springs on one level and carrying shelves extending inwardly to partially support other springs on another level, said bearing member being adapted when moved out of interlocking engagement with the side frame, to permit lateral withdrawal of said side frame at its lower portion. 105

10. The combination with a side frame provided with spring seats, of a spring bearing member supported by the lower portion 115 of the side frame and carrying upwardly projecting spring supports adapted to partially support springs which are also supported by the spring seats on the frame outside of the spring bearing member. 120

11. The combination with a side frame, of a spring bearing member supported by the lower portion of the side frame, partially on one level and partially on a higher level, springs supported on the higher level partially over the spring bearing member and partially outside of the sides of the latter, and other springs supported on a portion of said bearing member which is on a lower level. 125

12. The combination of a side frame having a central opening and at its lower portion provided with load supporting shelves on different levels, a spring supporting member supported partially by the lower shelf and partially by the higher shelf, and a spring mounted on said supporting member and so disposed on the higher portion thereof as to transmit a portion of its load to the frame inwardly beyond the higher shelf. ¹⁰
In testimony whereof, I have signed this specification.

GEORGE T. JOHNSON.
